(57) CLAIM

The ornamental design for a table, as shown and described.

DESCRIPTION

FIG. 1 illustrates an isometric view of the table, according to an embodiment of the present invention.

FIG. 2 illustrates a bottom plan view of the table, according to an embodiment of the present invention.

FIG. 3 illustrates a front elevational view of the table, according to an embodiment of the present invention; and, FIG. 4 illustrates a left side elevational view of the table, according to an embodiment of the present invention.

The right side elevational view of the table is a mirror image of the left side elevational view of FIG. 4.
